DESIGN FOR A HEELPLATE FOR BOOTS AND SHOES

William E. Strobel, Maplewood, N. J., assignor to
Sacks-Barlow Foundries, Inc., Newark, N. J., a
corporation of New Jersey

Application March 1, 1944, Serial No. 112,760

Term of patent 14 years

(Cl. D7—5)

To all whom it may concern:

Be it known that I, William E. Strobel, a citizen of the United States, residing at Maplewood, in the county of Essex and State of New Jersey, have invented a new, original, and ornamental Design for a Heelplate for Boots and Shoes, of which the following is a specification, reference being had to the accompanying drawing, forming a part thereof.

In said drawing:

Fig. 1 is an obverse face view, Fig. 2 is a front edge view, and Fig. 3 is a side edge view, of a heelplate for boots and shoes embodying my new design.

I claim:

The ornamental design for a heelplate for boots and shoes, as shown.

WILLIAM E. STROBEL.
